UNITED STATES PATENT OFFICE.

WILLIAM FARR GOODWIN, OF STELTON, NEW JERSEY.

ROTARY VALVE.

SPECIFICATION forming part of Letters Patent No. 278,790, dated June 5, 1883.

Application filed July 26, 1882. (No model.)

To all whom it may concern:

Be it known that I, WILLIAM FARR GOODWIN, of the town of Stelton, in the county of Middlesex and State of New Jersey, have invented certain new and useful improvements in oscillating valves for steam-engines in which the induction and exduction valves are operated independently of each other, and more especially for such as that patented by me, patent 5 dated June 7, 1881, and numbered 246,446, to which latter I will hereinafter refer for comparison; and my improvements have for their objects the thorough lubrication of the valves without waste of oil or other unguent matter, 10 and to provide a means for the valve to lift from its seat to admit the escape of water from the cylinder in case the water in the cylinder should be caught between the closed valve and the advancing piston to avoid damage by breaking, which might happen if no provision were 15 made for the escape of water with such valves; and the following is a full, clear, and comprehensive description of my improvements, reference being had to the accompanying two 20 sheets of drawings, in which—

Figure 1 is a sectional view of the front head of a cylinder, showing my improved valves and the ports and passages in the cylinder-head leading to and from the cylinder-valves; also 25 showing the form of the valve and valve-chamber, and the means provided to conduct and retain the steam-pressure and the oil or unguent matter to the back of the valve or valves in my improved engine, the section being taken on one side of the piston-rod on line B, Sheet 2. Fig. 2 is a similar sectional view of the other or opposite head of the cylinder, showing modifications of my improved valves. Fig. 3 is a 30 similar view of the valves V of Fig. 2 or V⁴ of Fig. 1, showing the open passage P, through which steam passes to or from the interior of the cylinder if those forms of valves are used. Fig. 4 is a similar view of valve V³, shown in section in Fig. 1, used only for the 35 induction-valve, the port-passage P being enlarged and made of larger area for the purpose of counterbalancing the large area of the back of the valve, upon which latter the steam presses to hold the valve steam-tight upon its 40 seat. Fig. 5 is a longitudinal sectional view on line G, Fig. 6, of the valve V, shown in

cross-section on line B, Fig. 5, showing the rock-shaft K, by which the valve is rocked, in its place in the valve V, and showing the space M, between the valve and the rock-shaft, containing the spring L. Said space permits the valve-face O to lift from its seat to permit the water to escape, also showing the mode of reinforcing the ends of the valves with bands Q and filling the top of the rock-shaft recess with 55 the strengthening-piece R, if desirable, in large valves. Fig. 6 is an end view of the valve V with its rock-shaft K. Fig. 7 is a section of the same through line A of Fig. 5.

Similar letters of reference indicate similar 60 parts in the several figures.

I will first describe the objects and nature of my invention, and then its mode of construction and operation.

In my improved steam-engine patented June 7, 1881, above referred to, I have thoroughly provided against waste of steam in the manner set forth in the said patent. In my said patent I also provided a means for lubricating the valves by extending the ends of the latter so 70 as to form journals, the bearings of which, corresponding to the seat of the valve and being constantly supplied with oil, serve to ease the movement of the valve, and the oil, working from the ends or journal-bearings of the said 75 valves onto the seats of the latter, serves to lubricate the said valve-seat for the induction-valve, while in the exhaust-valves of the four-valve engine shown in Figs. 1, 2, and 3 of my 80 said patent the oil is retained upon the backs of the exhaust-valves in like manner as shown in Fig. 1, valve V¹, of this my present improvement, the kind of engine in which my present improvement is designed to be used. The advantage of locating the valves in the heads of 85 the cylinder and all the improvements relating to the valves patented in the said patent being fully and comprehensively described and illustrated in my aforesaid patent, therefore I will not repeat its description, but will simply refer to the specification and drawings of the 90 said patent in my description of the difference between the improvements therein patented and those now sought to be patented and described in this my present specification. In 95 my Patent No. 242,446 the steam from the induction-passage B surrounds the exhaust-valve

V, to hold the latter upon its seat, while in this improvement the live steam passes to the back of the induction-valves V and V' through a separate passage, F, for the purpose of holding the valve upon its seat. In my said patent the induction-valve has one bridge, which rests upon the seat of the valve-chamber, and admits steam into the cylinder by moving off the port P, which leads from the valve-chamber into the cylinder, and closes the same port by moving back over the latter, leaving the passage which admits the steam to the valve-chamber constantly open, while the induction-valve of this improvement has two bridges or seats, similar to the exhaust-valves of my said patent, which inclose both of the passages into and out of the valve-chamber. Hence my first object in making this improvement is to insure as thorough lubrication without waste to the induction-valves of my improved engine as is attained in the exhaust-valves of the said patent by using the same kind of valve in both cases; and my second object is to balance the induction-valves, as nearly as is desirable, to insure steam-tight joints, by nearly equalizing the area of the pressure-surface upon both the inside and outside of the valve; and my third object is to provide a means for the valves to lift from their seats to permit water to escape; and my fourth object is to provide an exhaust-valve in said improved engine which will be held upon its seat steam-tight by the varying pressure of the expanding steam in the cylinder, with very little waste, the steam-space around the valve being very small, and the outward pressure being only equal to the area of the exit-port which leads outward from the valve-chamber.

The nature of my invention consists in the peculiar construction and arrangement of the mechanism and form of the valves, their seats and chambers, and the passages by which steam and oil are conducted to the back of the valves, and the cranked rock-shaft and recessed valve by means of which the valve is permitted to lift from its seat, and the combined construction and arrangement of the induction-valves and steam-passages in such manner that the steam passes into the cylinder under the valve in like manner as it passes out of the cylinder under the exhaust-valve, and the pressure of steam which holds the valves steam-tight upon their seats remains constant behind the valves, and does not pass into or out of the cylinder, and the oil remains in the valve-chamber behind the valve until used without being carried into and through the cylinder by passing steam or otherwise wasted.

By referring particularly to the Figs. 1, 2, 4, 5, and 3 of the drawings of my said patent, and to the several figures of the drawings of this specification, and making a careful comparison of the nature, construction, and arrangement of the valves and their appurtenances, and the objects sought to be attained in both cases, the nature and importance of this my improvement will be easily understood.

In Fig. 1 of the drawings of this specifi-

tion steam is admitted to the backs of both the induction and the exhaust valves through the passage F, leading from the top of the cylinder-head down to the exhaust-valve, and a passage, F', leading from the passage F to the valve-chamber behind the induction-valve admits steam-pressure to the latter to press the valve steam-tight upon its seat. Oil is also admitted to the valve-chambers through the said passages F and F'. The bridges of the induction-valves straddle and inclose both the port-passages E and P, through which steam passes into and out of the valve-chamber in its course into the cylinder, the bridges of the induction-valve being wide apart for the purpose of affording a large area of pressure-surface to counterbalance the pressure upon the large surface on the back of the valve. This valve is more economically lubricated and balanced, and less steam wasted thereby than by the common oscillating valves, which are used to good advantage as compared with other more wasteful valves. In the common oscillating-valve engine the four valves are located on the sides of the cylinder near the ends thereof, and the four superfluous steam-spaces in the steam-passages outside of the piston-space are very considerable, and contain a large number of cubic inches of steam, which latter occupies the said superfluous spaces at cylinder-pressure during the stroke of the piston, and the valves of the said common oscillating-valve engine, being surrounded by steam, can only be lubricated by the oil mingling with the steam. The pressure upon the induction-valves of the common oscillating-valve engine varies as the pressure in the cylinder varies, and is nearly equal at the end of each stroke to boiler-pressure over the area of the inlet-port. Thus it is obvious that there is an excess of pressure and consequent friction and wear with the induction-valves of the common oscillating-valve engine which is not found in my improved balanced induction-valves, in which latter the induction-valves are always balanced by the live-steam pressure upon both sides of the valve at the same time, with the necessary preponderance to hold the valves upon their seats and with no waste of steam whatever, there being no unnecessary space between the valve and piston at the end of the stroke of the latter. The piston-ridges, protruding through the thickness of the cylinder-head toward the valve, fill the ports and continue to occupy that amount of space in the cylinder. Hence there is no waste of steam or unnecessary pressure or wear upon the induction-valves. The exhaust-valves of the common oscillating-valve engine are wasteful of steam as compared with my improvement. In the common oscillating-valve engine the exhaust-valves are located on the sides of the cylinder, near the ends thereof, in like manner as the induction-valves, the port-passages being necessarily larger than that of the induction-valves to admit the free passage of steam from the cylinder. The steam enters and occupies the large

120
125
130

exhaust-spaces between the valves and the piston-space, and in addition to that it also enters and occupies the space in the valve through which the steam passes out of the cylinder.

5 The waste thus occasioned by leaving open so large a space in the valve to be occupied by steam as it enters the cylinder at boiler-pressure outside of the piston-space, according to facts demonstrated by the common oscillating-
10 valve engine as compared with other more wasteful engines, is very great, while in my improved engine there is no superfluous spaces outside of the piston-space, and consequently there is no waste of steam from such cause as
15 found in the common oscillating-valve and other engines. My improved valves, being located in the heads of the cylinder, occupy all the superfluous space between the valves and piston; and the advantages can be ascertained
20 by the difference between my improved engine and other engines. In my engine one-eighth of an inch clearance between the piston, cylinder-head, and valves being sufficient to admit the full pressure of steam to the whole area of
25 the piston in ample time to take full effect upon the latter at the proper time, and all superfluous space in excess of this in any steam-engine is wasteful, and the waste is in proportion to the excess of clearance and superfluous space
30 between the valve and the piston-space as compared with any engine in which there is no excess of superfluous clearance or space, as before explained.

The plan shown in Fig. 1, valve V^1 , for introducing the live steam to the back of the exhaust-valve V^1 , is good, and its merit consists in simplicity of construction and thorough lubrication; and while the pressure upon the back of the valve is constant and uniform, and is
35 therefore greater than the varying pressure of the expanding steam upon the back of the exhaust-valve V^2 , the greater pressure is largely compensated by the copious and constant supply of oil which is retained upon the back

of the valve without wasting the latter, the oil causing the valve to move freely on its seat as well as lubricate its journals, and is particularly adapted for use in locomotives and other high-speed engines.

My improved valves would be well adapted to use with high-speed engines having but one cylinder-head, for the reason that no steam would be lost between the valve and piston-space.

Having fully described my invention, what I claim as new, and desire to secure by Letters Patent, is—

1. The combination of the oscillating valve, the balancing-recess, and independent steam-passage leading thereto, substantially as shown and described.

2. In combination with an oscillating valve having its ported face constantly open to the steam in the main port, of the balancing-recess and independent steam-passage leading thereto, substantially as shown and described.

3. In combination with an oscillating valve having a balancing-recess closed to the cylinder-ports, of an independent steam-passage leading to the said recess, and an oil-cup opening into said passages, whereby the valve is lubricated and the oil is retained in the recess, substantially as shown and described.

4. In combination with an oscillating valve, the rock-shaft, the valve proper, the independent valve-face, and the spring, whereby the valve-face is permitted to rise and allow the escape of water from the cylinder, substantially as shown and described.

5. In an oscillating valve, the combination of the rock-shaft R, the valve V, the independent face O, the spring L, and the bands Q, substantially as shown and described.

WILLIAM FARR GOODWIN.
